UNITED STATES PATENT OFFICE.

WILLIAM H. MILLSPAUGH, OF SANDUSKY, OHIO, ASSIGNOR TO THE PAPER & TEXTILE MACHINERY COMPANY, OF SANDUSKY, OHIO, A CORPORATION OF OHIO.

VACUUM PUMP.

Application filed June 28, 1923. Serial No. 648,218.

To all whom it may concern:

Be it known that I, WILLIAM H. MILLSPAUGH, a citizen of the United States, and a resident of Sandusky, county of Erie, and State of Ohio, have invented certain new and useful Improvements in Vacuum Pumps, of which the following is a specification.

This invention relates to pumps and particularly to cycloidal vacuum pumps.

Cycloidal vacuum pumps are used largely in paper mills for extracting water and other liquids from the paper sheet. The liquid extracted contains chemicals such as acids, alkalis, alum and lime water and also frequently contains grit from the grindstones used to grind the pulp. These chemicals and the grit injure the pump elements and casing by erosion and wear. Bronze parts have been used to overcome the deleterious effects of the chemicals, but bronze is a comparatively soft metal and is easily worn away by the grit.

This invention has for its salient object to provide a pump particularly adapted for paper mill service and having its parts so constructed that the liquid and foreign matter carried by the liquid will not injure or erode the pump elements or casing.

Further objects of the invention will appear from the following specification taken in connection with the drawings, which form a part of this application, and in which

Fig. 1 is an elevational view of a cycloidal pump constructed in accordance with the invention, and

Fig. 2 is a sectional elevation taken substantially on line 2—2 of Fig. 1.

The invention briefly described consists of a cycloidal vacuum pump comprising a casing and impellers mounted therein, the co-acting surfaces of the impellers and casing being so constructed that they will withstand wear and erosion due to the chemicals in the liquid passing through the pump. It has been found by experience that these elements can be constructed of ordinary gray cast iron and that if the iron of the castings is not machined, but the molecular structure of its outer crust or surface left undisturbed, this outer crust or surface will have the desired characteristics or, in other words, will withstand erosion and wear. It has also been found that if these surfaces are slightly

chilled they will have the desired characteristics. 55

Referring to the drawing, there is illustrated therein a cycloidal pump having a two-part casing 10, 11, the casing having an inlet opening 12 at the bottom thereof communicating with a chamber 13 to which are connected conduits 14. These conduits may be connected to suction rolls or suction boxes or to driers or other parts of the paper mill apparatus, or to any other form of apparatus where suction is desired. In the particular embodiment of the invention illustrated, the section 11 of the casing has a discharge shaft 15 provided with a laterally extending discharge conduit 16 and a vertically extending discharge conduit 17. 60

The pump casing has mounted therein cycloidal impellers 20, 21 mounted on shafts 22 and 23. 65

In the embodiment of the invention shown in Fig. 1, the pump is mounted on a base 24 having standards 25 and 26 and bearings 27 carried by the standards. The base and standards may be cast integral. 70

The pump casing and impellers are preferably formed of cast iron and particular attention is directed to the fact that the inner surface 28 of the casing and the outer surfaces 29 of the impellers are not finished or machined, except for length, but are left in undisturbed or unfinished condition in which they come from the mold after being cast. If desired, these surfaces may be chilled but it has been found by actual experience that the surface or crust formed on the castings possesses the desired characteristics and will withstand erosion and wear. 80

The surfaces of the casing heads 30 are chilled and ground, not removing all the chill that proper clearances be insured. 85

The pump above described operates in the usual manner. Water or liquid is drawn in through the conduits 14 and opening 12 and this liquid is forced through the casing into the discharge shaft 15. In operation most of the liquid will be discharged through the conduit 16 and the air will rise to the top of the discharge shaft 15 and will pass out through the conduit 17. 90

The particular construction of the pump is not material and other forms of pumps may be used as desired. It is, however, of primary importance to have the coacting

surfaces of the pump elements formed in the manner above set forth.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A cycloidal vacuum pump comprising a casing and impellers therein, said impellers and casing having cast iron, coacting surfaces, the skin of said coacting surfaces being undisturbed.
2. A rotary pump comprising a casing and cast iron impellers therein, the skin of the coacting surfaces of the impellers being undisturbed.
3. A pump comprising a casing and operative relatively movable elements therein,

said casing and elements being formed of cast iron and having the skin of their coacting surfaces undisturbed.

4. A pump comprising a casing and operative relatively movable elements therein, said casing and elements being formed of cast iron and having chilled, coacting surfaces, the skin of said surfaces being undisturbed.

5. A cycloidal vacuum pump comprising a casing and impellers therein, said impellers and casing being formed of cast iron and having undisturbed, chilled, coacting surfaces.

6. A rotary pump comprising a casing, and impellers therein, the coacting surfaces of the impellers being formed of cast iron with its molecular structure undisturbed by being left unfinished.

In witness whereof, I have hereunto set my hand this 12th day of June, 1923.

WILLIAM H. MILLSPAUGH.
